Primary Examiner—Doris Clark*Attorney, Agent, or Firm*—Fitch, Even, Tabin & Flannery[57] CLAIM

We claim the ornamental design for a seating housing, as shown and described.

DESCRIPTION

FIG. 1 is a perspective view of a seating housing showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is an enlarged perspective view.

The broken lines are for illustrative purposes only and form no part of the claimed design.
